CLAIM

The ornamental design for a golf mat, as shown and described.

DESCRIPTION

FIG. 1 is a perspective view of a golf mat, showing my new design;

FIG. 2 is a top, plan view thereof;

FIG. 3 is a bottom, plan view thereof;

FIG. 4 is a right, side elevation view thereof;

FIG. 5 is a left, side elevation view thereof;

FIG. 6 is a front elevation view thereof; and,

FIG. 7 is a rear elevation view thereof.

The golf mat is made of a material that has no appreciable thickness relative to its length and width.

The broken lines on the perimeter of the golf mat represent stitching and form no part of the claimed design.
